RELIEF-VALVE FOR STEAM-CYLINDERS.

1,110,378.

Specification of Letters Patent. Patented Sept. 15, 1914.

Application filed January 8, 1913. Serial No. 740,780.

To all whom it may concern:

Be it known that we, JOHN HEBER COYNE, a subject of the King of Great Britain, residing at Toronto, in the Province of Ontario and Dominion of Canada, and JOSEPH JAMES WORDEN, a subject of the King of Great Britain, residing at St. Thomas, in the Province of Ontario and Dominion of Canada, have jointly invented certain new and useful Improvements in Relief-Valves for Steam-Cylinders, of which the following is a specification.

Our invention relates to mechanism for supplying saturated steam to the cylinders of locomotives using superheated steam while drifting. At the present time many railroad companies are fitting their locomotives with superheaters, since the advantages of superheated steam have been found in practice to be very great. When working on saturated steam there is always sufficient free moisture present to provide for lubrication of valves and cylinders. With superheated steam a new problem arises on account of the lack of moisture. The steam is superheated until it becomes little more than a dry gas at a high temperature, and, in consequence, the packings are burned and cylinders and valves scarred because of lack of moisture for lubrication. It has been found that saturated steam admitted to the cylinders while the locomotive is drifting, or running idle, has in some degree remedied this trouble. Heretofore, manually operated devices have been proposed, and to some extent, used, for this purpose; and some mechanisms intended to be automatic in character have also been proposed. So far as we are aware, however, these automatic devices have depended upon atmospheric pressure to directly and immediately effect an opening of the saturated steam supply valve, as well as required the presence of check-valves; and owing to the great difference between atmospheric pressure and the high boiler pressures maintained on modern locomotives, a dependence upon atmospheric pressure alone to do this work is unsatisfactory, as requiring a high vacuum and a piston or diaphragm of considerable diameter to overcome the friction of pistons, packing rings, etc., and insure a satisfactory working of the apparatus.

Our present invention relates to relief valve mechanism of the automatic type, and

has for its main object to provide an improved mechanism more sensitive and reliable in its operation than any heretofore produced, and one which shall not require a system of check valves or a high vacuum to make it operative.

Our invention, in two practical forms in which it may be embodied, is illustrated in the accompanying drawings, in which—

Figure 1 is a vertical section through our improved valve taken on the line 1—1 of Fig. 2, and showing also a steam cylinder and valve-chest, with a pipe connection from one end of the latter to the relief valve; the parts being shown in their normal or idle position. Fig. 2 is a section at right angles to that of Fig. 1 on the line 2—2 of Fig. 1. Figs. 3 and 4 are views similar to Figs. 1 and 2, respectively, but showing the parts in working condition. Figs. 5 and 6 are views corresponding with Figs. 1 and 2, respectively, and illustrating a modified form of the invention.

Refer first to Figs. 1 to 4 inclusive, 5 designates a cylinder closed by heads or caps 6 and 7, and having cast integral therewith one wall 8 of a diaphragm chamber 9, the other wall of which is constituted by a cap or cover 10 secured to the wall 9 by screws 11. Within the diaphragm chamber 9 is mounted a diaphragm 12, which is clamped by a nut 13 between the diaphragm plate 14 and a washer 15 on a diaphragm stud 16. This stud has a sliding bearing in the diaphragm cover 10 and in the outer end of a spring cap 17; and through stud 16, nut 13, and diaphragm plate 14, the diaphragm is normally held against the diaphragm cover 10, as shown in Fig. 1, by means of a coil spring 18 surrounding said stud 16, one end of said spring abutting against the inner end of a collar 19 through which the stud 16 passes, and which is screwed into an internally threaded boss 20 on diaphragm cover 10, the outer end of said collar receiving the spring cap 17. The outer end of spring 18 abuts against a flange or collar 21 on stud 16; and the force of the spring 18 may be adjusted at will by loosening the cap 17, and turning the collar 19 by means of a key 22, after which the cap 17 is jammed down sufficiently to lock the collar 19 against turning. The diaphragm cover 10 is provided with a series of holes 23 to admit atmos-

pheric pressure to the outer side of the dia-
phragm. The diaphragm chamber 9 is con-
nected by a port 24 to a pipe-socket 25
formed in the lower portion of the dia-
phragm wall 8; and from said socket a pipe
connection 26 extends to and communicates
with one end of the valve chest 27 of a lo-
comotive cylinder 28.

Within the casting which forms the dia-
phragm wall 8 and cylinder 5, and beneath
the latter, is formed a control-valve cham-
ber 29, in which is located the control-valve
30 kept normally closed by a spring 31.
The stem of valve 30 extends through the
valve seat into the diaphragm chamber 9
to such an extent that its end just misses
the inner end of the diaphragm stud 16
when the latter is in the normal position
shown in Fig. 1.

On the upper side of the cylinder 5 is an
internally threaded boss 32 that receives a
steam pipe from the boiler supplying satu-
rated steam; and on the lower side of the
cylinder 5 directly opposite the boss 32 is a
cored passage 33, with the lower end of
which communicates a pipe 34 that leads to
and communicates with the steam cylinder
28, preferably tapping the latter centrally
thereof, through a port 35 as shown in Figs.
1 and 3.

Within cylinder 5 is a cylinder lining 36
that is formed with ports 37 in its upper
side registering with the boss 32, and with a
port 38 in its lower side that registers with
the upper end of the cored passage 33.
Slidably mounted in a slide-way 39 formed
in the lower side of the bushing 36 is the
saturated steam supply valve 40.

Within the cylinder cap 6 is a lining 41;
and within the chamber formed by the lin-
ings 36 and 41 is mounted a differential pis-
ton unit comprising a smaller piston 42 that
travels within the lining 41 of the cylinder
cap 6, a larger piston 43 that travels within
the somewhat enlarged outer end portion of
the lining 36, and a connecting stem 44. On
the piston stem are formed shoulders 45 and
46 that engage opposite ends, respectively,
of the slide valve 40 to actuate the latter.
The former in the opening movement and
the latter in the closing movement of said
valve. The outer face of piston 43 is re-
cessed to receive one end of a coil compres-
sion spring 47, which latter is supported on
a hollow stud 48 secured to the end cap 7,
and abutting at its outer end against the
latter. In the outer end of the cylinder cap
6 is a vent opening 49 terminating at its in-
ner end in a valve seat 50 that is normally
closed by a valve 51 carried by the smaller
piston 42 and pressed outwardly by a
spring 52.

The steam supply valve 40 is formed with
upwardly extending sides 40' straddling the
central portion of the piston stem 44; and

between said side walls, at the ends of the
latter, are mounted pins 53 that support a
bow spring 54 that bears on the upper side
of the cylinder lining 36, and holds the
valve 40 to its seat.

In the lower side of the cylinder wall 5 is
a cored passage 55 that communicates freely
at one end with the control-valve chamber
29. This passage 55 communicates by a
port 56 with the outer end of the cylinder in
which the larger piston 43 operates, and
also communicates by a much smaller port
57 with the inner end of said cylinder.

The operation of the apparatus is as fol-
lows. The normal or idle position of the
parts is as shown in Figs. 1 and 2. In this
position, the differential piston unit is in
equilibrium, owing to the fact that the
boiler pressure existing between the two pis-
tons finds its way to the outer face of the
larger piston through port 57, passage 55
and port 56, and to the outer face of the
smaller piston by leakage around the piston
ring of the latter. The spring 47 acts to
keep the piston unit and valve 40 in normal
position and prevent said parts from jarring
back and forth. As soon as the throttle of the
engine is closed and the latter begins to drift,
a vacuum is formed in the engine cylinders,
and the suction created thereby is transmitted
through the valve chest 27, pipe 26, socket
25 and port 24 to the diaphragm chamber 9.
Atmospheric pressure acting through the
holes 23 upon the outer face of diaphragm
12 forces the latter over to the position
shown in Fig. 3. This opens the control
valve 30, which releases the pressure on
the outer face of the larger piston 43
through port 56 and passage 55 much faster
than the pressure between the pistons can
be reduced through port 57, owing to the
greater size of port 56. A condition thus
arises in which substantially boiler pressure
exists between the pistons and on the outer
face of the smaller piston, while substan-
tially atmospheric pressure exists on the
outer face of the larger piston. This forces
the piston unit to the right, to the position
shown in Fig. 4, carrying the slide valve
40 with it, and uncovering the port 38. This
movement of the piston unit, of course, at
the start opens the vent port 49 reducing
the pressure on the outer face of the smaller
piston to atmospheric pressure; but as the
larger piston is about twice the area of the
smaller piston, the result is to continue the
movement of the piston unit to the right and
maintain it in that position so long as the
suction in the diaphragm chamber is main-
tained. Saturated steam is thus allowed to
flow freely through port 38, passage 33,
pipe 34 and port 35 to the engine cylinder
28, in sufficient quantities to lubricate the
latter. This continues until the suction in
the diaphragm chamber 9 ceases, due to

either the stopping of the locomotive or the opening of the throttle valve; in which case the spring 18 will move the diaphragm 12 and stud 16 back into normal position, thus permitting spring 31 to close control-valve 30, which will allow pressure to again accumulate on the right of the larger piston 43 until it is sufficient, with the energy of spring 47, to shift the piston unit back to the normal position, thus closing the supply port 38 and the vent 49, and restoring the parts to normal idle position.

It will thus be seen that the differential piston unit and its cylinder constitute in effect a normally idle steam motor for actuating the valve that controls the supply of saturated steam to the steam cylinder, and that the control valve, diaphragm, diaphragm chamber, steam chest connection to the latter, and differential steam ports (56 and 57) and their common communication to the diaphragm chamber co-operatively constitute a means for controlling the operation of the said steam motor that is set in operation upon the creation of a suction or vacuum effect in the engine cylinder. It will also be manifest that the diaphragm chamber, diaphragm, and diaphragm stud constitute in effect a normally idle diaphragm motor, called into action by a suction or vacuum effect in the engine cylinder, for opening the control valve, that, in turn, governs the position and movements of the differential piston unit.

It may here be noted that the valve 51 carried by the smaller piston is provided simply to prevent any leakage of steam from the apparatus when it is in its normal idle position, in which it remains the greater part of the time. This valve has no effect on the operation of the device, and might be omitted in so far as it affects the theoretical working, although, of course, the vent 49 is essential in order to effect a positive closing of the slide valve 40. The different parts of the apparatus have been so arranged as to give a hydraulic grade such that the condensation in the various chambers, ports and passage ways of the structure will work downward and out through the suction pipe 26.

Figs. 5 and 6 illustrate a slightly modified and simplified form of the invention, which employs the same diaphragm control, but replaces the horizontal slide valve and differential piston unit by a vertically disposed valve and piston unit, and wherein the smaller piston and the valve controlling the saturated steam supply are combined in a single structure. In said figures 5' designates the cylinder of the differential piston, 7' the head closing the upper end thereof and containing the spring 47' which bears against the upper face of the larger piston 43'. 55' is the cord passage-way that

communicates at its lower end with control-valve chamber 29', and, by relatively large and small ports 56' and 57' with opposite sides of the large piston 43'. 32' designates the internally threaded boss that receives a 70 steam pipe from the boiler supplying saturated steam. The lower end of the vertical differential piston cylinder 5' communicates directly with the saturated steam supply pipe 34'; and in the lower portion of 75 cylinder 5', below the lateral steam supply port thereof, is fitted a valve seat 58 that operates with a valve 59 formed on the differential valve stem 44', which valve 59 combines the functions of the smaller piston 42 and the slide valve 40 of the construction previously described and shown in Figs. 1 to 4 inclusive. When the piston unit of this construction is in the normal idle position shown in Fig. 6, the excess steam 80 pressure on the upper face of the larger piston 43' holds the piston unit in such normal idle position in which the saturated steam supply is cut off by the valve 59. The valve 59 opens under a suction effect 85 created in the diaphragm chamber, when the engine is drifting in precisely the same way as described in connection with the form of the invention shown in Figs. 1 to 4 inclusive. Although the valve 59 is intended to have the same function and action as the smaller piston 42 of Figs. 2 and 4, it will, of course, be in the steam current while open; and since the piston unit is substantially in equilibrium (except 90 for gravity) when the valve is open and after the suction has ceased through stopping of the locomotive or closing of the throttle valve, spring 47' is employed to effect a prompt and positive closing of the 95 valve. This last described form of the invention is somewhat simpler than the first described form in that the saturated steam supply valve and smaller piston of the differential piston unit are combined structurally and functionally, and the vent 49 and valve 51 controlling the same, shown in Fig. 4, are dispensed with. Instead of saturated steam, our improved relief valve might be used to handle boiler water which 100 could be sprayed into the engine cylinders for the purpose of cooling them and furnishing lubrication.

It will be evident to those skilled in the art that the various details of structure and arrangement as herein shown and described might be somewhat modified without involving any departure from the principle of the invention or sacrificing any of the advantages thereof. Hence, we do not limit 110 the invention to the exact details shown and described except to the extent clearly indicated in specific claims.

We claim—

1. In a relief valve mechanism for steam 120

cylinders, the combination with a conduit for saturated steam between the boiler and steam cylinder, of a valve controlling said conduit, a differential-piston motor for actuating said valve, the piston unit of said motor being constantly subject to boiler pressure on both sides of both piston heads thereunder and normally in equilibrium thereunder, and means set in operation by a suction effect in the engine cylinder for destroying the condition of equilibrium of said piston unit.

2. In a relief valve mechanism for steam cylinders, the combination with a conduit for saturated steam between the boiler and steam cylinder, of a valve controlling said conduit, a differential-piston motor for actuating said valve, the piston unit of said motor being constantly subject to boiler pressure on both sides of both piston heads thereunder and normally in equilibrium thereunder, a control valve governing the position and movements of said differential piston unit, and a normally idle diaphragm motor called into action by a suction effect in the engine cylinder for opening said control valve.

3. In a relief valve mechanism for steam cylinders, the combination with a conduit for saturated steam between the boiler and steam cylinder, of a valve controlling said conduit, a differential piston motor for actuating said valve, the piston unit of said motor being constantly subject to boiler pressure on both sides of both piston heads thereunder and normally in equilibrium thereunder, a spring acting upon said piston unit to prevent jarring thereof and maintain the same normally in valve closing position, a control valve governing the position and movements of said differential piston unit, and a normally idle diaphragm motor called into action by a suction effect in the engine cylinder for opening said control valve.

4. In a relief valve mechanism for steam cylinders, the combination with a conduit for saturated steam between the boiler and steam cylinder, of a valve controlling said conduit, a differential piston motor for actuating said valve, the piston unit of said motor being constantly subject to boiler pressure and normally in equilibrium thereunder, a diaphragm chamber, a diaphragm

therein exposed to atmospheric pressure on one side thereof, a suction pipe from the engine cylinder communicating with said diaphragm chamber on the other side of said diaphragm, a passage leading from said diaphragm chamber and communicating with the cylinder of said differential piston motor on opposite sides of the larger piston thereof through relatively small and large ports, respectively, a spring acting on said diaphragm in a direction to oppose atmospheric pressure thereon and a control valve in said passage adapted to be opened by said diaphragm under atmospheric pressure upon the creation of a suction effect in said suction pipe.

5. In a relief valve mechanism for steam cylinders, the combination with a conduit for saturated steam between the boiler and steam cylinder, of a valve controlling said conduit, a differential piston motor for actuating said valve, the piston unit of said motor being constantly subject to boiler pressure and normally in equilibrium thereunder, a diaphragm chamber, a diaphragm therein exposed to atmospheric pressure on one side thereof, a suction pipe from the engine cylinder communicating with said diaphragm chamber on the other side of said diaphragm, a passage leading from said diaphragm chamber and communicating with the cylinder of said differential piston motor on the inner and outer sides of the larger piston thereof through relatively small and large ports, respectively, a diaphragm stud secured centrally to said diaphragm, a spring engaging said diaphragm stud in a direction to oppose atmospheric pressure on said diaphragm, and a control valve normally closing communication between said passage and said diaphragm chamber, said control valve having a projection adapted to be struck by the inner end of said diaphragm stud to unseat said control valve under the action of atmospheric pressure on said diaphragm upon the creation of a suction effect in said suction pipe.
